Primary Examiner — T Chase Nelson*Assistant Examiner* — Christine Tucci(74) Attorney, Agent, or Firm — Schwabe, Williamson & Wyatt, P.C.(57) CLAIM

I claim the ornamental design for a shoe, as shown and described.

DESCRIPTION

FIG. 1 is a front, bottom perspective view of a shoe, showing my new design;

FIG. 2 is a bottom view thereof;

FIG. 3 is a rear, bottom perspective view thereof; and,

FIG. 4 is a right side view thereof.

The broken lines depict features of the shoe that form no part of the claimed design.
